UNITED STATES PATENT OFFICE

CALVIN C. WILLIAMS, OF PHILADELPHIA, PENNSYLVANIA

VALVE ACTUATING MECHANISM

Application filed March 17, 1926. Serial No. 95,361.

This invention relates to an improved valve actuating mechanism of the general character disclosed in my copending application for a similar invention, filed November 26, 1924, Serial No. 752,400, and seeks, among other objects, to provide an overhead valve mechanism wherein wear and looseness between the parts will be automatically taken up and rattling prevented.

10 The invention seeks, as a further object, to accomplish the automatic expansion and contraction of the push rod employed without the necessity for rotating any of the parts.

15 Still another object of the invention is to embody a novel slip joint in the push rod, of such construction that the inertia of the parts will provide sufficient thrust to effect the partial slipping of the joint and corresponding contraction of the push rod.

20 And the invention seeks, as a still further object, to provide a mechanism composed of few and simple parts, which will meet the extreme demands of hard usage and which may be readily installed upon engines now in use in lieu of the usual overhead valve mechanisms.

25 Other objects of the invention not specifically mentioned in the foregoing will appear during the course of the following description.

In the accompanying drawings:

Figure 1 is a vertical sectional view showing my improved mechanism in connection with a conventional overhead valve.

Figure 2 is a view similar to Figure 1, but showing the push rod of the mechanism contracted.

Figure 3 is a transverse sectional view on the line 3-3 of Figure 1, looking in the direction indicated by the arrows.

Figure 4 is a vertical sectional view showing a slight modification of the invention.

Figure 5 is a transverse sectional view on the line 5-5 of Figure 4, looking in the direction indicated by the arrows.

Referring now particularly to Figures 1, 2 and 3 of the drawings, the numeral 10 indicates a fixed tappet guide, and slidably through said guide is a tappet 11 operable

by a cam shaft 12. At its upper end, the tappet is provided with a socket 13 and abutting the upper terminal of the tappet is the joint cup 14 of the slip joint of the push rod employed, said cup having a stud 15 fitting in the socket. The joint cup is formed with a conical inner face 16, and projecting from the upper end of said cup is an overhanging annular flange 17.

A lining with the tappet 11 is the push rod stem 18, provided at its lower end with an enlarged cylindrical foot 19 terminating in a joint cone 20 which extends into the cup 14 axially thereof, and formed on the upper end of the stem is a ball head 21. Resting on the upper end of the foot 19 is a housing 22 which, at its lower end, is of a diameter to freely receive the flange 17 of the cup 14 and extends downwardly over said cup, while at the upper end of said housing is an upstanding sleeve 23 fixed to the stem 18. Preferably, the push rod stem is, as shown, formed of upper and lower sections, the meeting ends of which are driven into the sleeve 23 so that the sections are thus rigidly connected with each other by said sleeve. Formed in the housing near its lower end is an internal annular groove and engaged in said groove is a split resilient stop ring 24 disposed to engage the flange 17 of the cup 14 for limiting the housing and the push rod stem in their upward movement independently of the cup.

Disposed in the cup 14 to lie between the face 16 thereof and the cone 20 of the push rod stem is a series of conical or longitudinally tapered rollers 25, and slidably fitting the foot 19 of said stem is a follower 26 provided at its lower end with an annular flange 27 which is beveled to seat flat against the larger upper ends of said rollers. Resting at one end against the upper end of the housing 22 and at its opposite end against said flange is a take-up spring 28.

I have shown the present mechanism in connection with a conventional overhead valve 29 which is slidably supported by a cage 30, and normally holding the valve closed is a spring 31, this spring being of far greater strength than the spring 28. Mount-

ed to coact with the upper end of the valve stem is a rocker 32 and, as will be observed, the outer end of the rocker is provided with a socket to accommodate the ball head 21 of the push rod stem so that when the push rod is lifted the rocker will be actuated for opening the valve.

As will now be seen, the spring 28 will tend to lift the stem 18 of the push rod for taking up any looseness between said stem and the rocker 32 as well as any looseness between the rocker and the stem of the valve 29, and will also tend to advance the rollers 25 downwardly within the cup 14 to bind between the face 16 of said cup and the cone 20 of the stem. Accordingly, play between the cone and the cup will be taken up and all looseness eliminated.

Assuming now that the tappet is raised, as shown in Figure 2, it will be seen that the upward thrust of the tappet will be transmitted directly to the rollers 25 and, of course, at the instant such upward thrust is transmitted to said rollers, the push rod, rocker, and valve will be at rest. Accordingly, the inertia of these parts will be sufficient to maintain the push rod stationary momentarily and oppose the upward thrust of the tappet with sufficient force to cause an upward endwise slipping of the rollers with a coincident upward movement of the cup independently of the cone. The follower 26 is, therefore, shifted upwardly by the rollers to compress the spring 28, and due to the difference in the angularity of the face 16 of the cup and the face of the cone, the rollers are, of course, independently shifted upwardly a distance greater than the independent upward movement of the cup. The push rod is thus automatically contracted, but as the tappet continues in its upward movement and the inertia of the push rod stem, rocker, valve, and valve spring is overcome, the upward slipping of the rollers is arrested substantially at the instant the push rod stem begins to yield to the upward movement of the tappet, when said rollers wedge between the face 16 of the cup and the cone 20 to provide a rigid connection between said cup and the push rod stem so that the valve is opened.

Due to the automatic contraction of the push rod as the valve is opened, the opening travel imparted to the valve will be correspondingly shortened. Accordingly, upon the return of the tappet downwardly, the valve will seat before the tappet reaches the bottom of its throw so that the stem 18 of the push rod will be relieved of the downward pressure exerted thereon by the valve spring 31. As a result, the spring 28 will, as the tappet completes its downward movement, expand for lifting the stem 18 of the push rod and again shifting the rollers downwardly within the cup, so that the parts will be re-

turned to their original position, as shown in Figure 1, while all looseness between the parts will be automatically taken up. Rattling will thus be effectually prevented. As will be seen, should the valve fail to seat properly, the push rod will automatically expand to compensate for the shortened closing travel of the valve while, when the valve is subsequently permitted to move into engagement with its seat, the push rod will automatically contract to compensate for the increased closing travel of the valve.

In Figures 4 and 5 of the drawings, I have shown a slight modification of the invention wherein the joint cup is rotated to assist in the contraction of the rod. A cam shaft is indicated at 33 and one of the cams thereof at 34. Disposed above the cam shaft is a fixed push rod guide 35 having an oblique bore therethrough, and slidable through said bore is a tappet 36 having a foot 37 to coact with the cam 34. The tappet is thus tilted with respect to the vertical in the plane of the cam shaft so that the cam 34 will engage the foot 37 of the tappet at one side thereof only. Accordingly, as will be seen, each time the tappet is raised by the cam, the tappet will be slightly rotated. It is to be understood that the tappet need be tilted vertically but very little and the showing of Figure 4, as regards the inclination of the tappet, is greatly exaggerated in order to better bring out the feature.

Formed in the upper end of the tappet is a socket 38, and mounted at the upper terminal of the tappet is a joint cup or member 39 having a stud 40 which is freely received in said socket. This stud is provided at its lower end with a notch 41, and extending across the socket 38 of the tappet is a pin 42 which is freely received in said notch to coact with the stud for turning the cup as the tappet is rotated. The cup 39 is provided with a conical face 43, and except for the notch 41 in the stud 40 of the cup, said cup is identical with the cup shown in the prior embodiment of the invention. Extending into the cup is the joint cone 44 on the foot 45 of the push rod stem 46, the stem being provided at its upper end with a ball head 47 to coact with the rocker indicated at 48. Disposed within the cup to coact with the cone 44 is a series of tapered rollers 49, and fixed to the stem 46 is a housing 50 which extends downwardly over the cup and carries a stop ring 51. Coacting with the rollers 49 is a follower 52, and pressing the follower downwardly is a spring 53. All of these parts are identical with corresponding parts as employed in the prior embodiment of the invention and function in like manner. Fixed to the stem 46 to coact with the cylinder block of the engine or other adjacent part thereof is a projecting stop pin 54 limiting the stem against rotation with the tappet 36 and cup 130

39. Accordingly, as will be seen, as the cup 39 is raised and rotated by the tappet and the rollers 49 are shifted upwardly within the cup, said rollers will be rotated within 5 the cup around the clutch cone 44. This rotation of the rollers will tend to produce as well as pronounce the momentary upward slipping of the rollers between the face 43 of the cup and the cone so that as the push 10 rod is raised, said rod will be automatically contracted.

Having thus described the invention, what I claim is:

1. In valve actuating mechanism, a cup, 15 a cone extending into the cup, and rollers disposed between the cone and cup to coact therewith for limiting the cup against movement toward the cone but shiftable to permit such movement by thrust exerted on the cup.

2. In valve actuating mechanism, a cup, a cone extending into the cup, rollers disposed between the cone and cup to coact therewith for limiting the cup against movement toward the cone but shiftable to permit such movement by thrust exerted on the cup, and 25 a spring resisting the shifting of said rollers.

3. In valve actuating mechanism, a cup, a cone extending into the cup, rollers disposed between the cone and cup to coact therewith for limiting the cup against movement toward the cone but shiftable to permit such movement by thrust exerted on the cup, a follower coacting with the rollers, and a spring acting on the follower for resisting 35 the shifting of said rollers and tending to expel the cone from said cup.

4. In valve actuating mechanism, a tappet, a cup carried thereby and provided with a conical face, a push rod stem having a cone 40 extending into the cup, conical rollers lying between the cone and said face to coact therewith for resisting movement of the cup toward the cone but shiftable to permit such movement by thrust of the tappet, a follower 45 coacting with the rollers, and a spring acting on the follower for resisting the shifting of the rollers and tending to expel the cone out of the cup.

5. In valve actuating mechanism, coacting members, means coacting with said members for limiting one of the members against movement toward the other member but shiftable to permit such movement by thrust 70 exerted on one of the members, means for rotating one of the members and accelerating the shifting of said first mentioned means, and means for limiting the other of the members against rotation. 75

6. In valve actuating mechanism, the combination with a cam shaft having a cam, of a tappet inclined with respect to the shaft for engagement by the cam at one side thereof only whereby the tappet will be rotated, coacting members, one of said members being rotatable with the tappet, means coacting with said members for limiting one of the members against movement toward the other member but shiftable to permit such movement by the thrust of the tappet, and means limiting the other of said members against rotation. 85

7. In valve actuating mechanism, companion members, one of which is provided with an internal cone shaped face and spacing rollers interposed between said members to coact with said face and shiftable by the wedging action of one of said members to 95 permit movement of the members toward each other.

8. An automatic take-up device including relatively movable members, one of which is provided with an inclined face, and rollers 100 disposed between said members to coact with said face and shiftable for spreading said members apart.

9. An automatic take-up device including relatively movable members, one of which is provided with an inclined face, rollers disposed between said members to coact with said face and shiftable for spreading said members apart, and yieldable means resisting retrograde movement of said rollers. 105 110

In testimony whereof I affix my signature.
